CORE BARREL

Alfred Muhlbach, Los Angeles, Calif.

Application December 24, 1938, Serial No. 247,625

4 Claims. (Cl. 255—72)

This invention relates to core barrels, such as are used in connection with core drills in oil well drilling, for securing sections of the formation through which the drill is passing.

More particularly, the invention relates to that type of core barrel having an inner and an outer shell, the inner shell remaining stationary with the core, while the outer shell rotates with the drill.

It is another object of this invention to provide an improved bearing structure for supporting the inner shell in such a core barrel.

It is a principal object of this invention to provide an improved and simplified core barrel of this type.

It is another object of this invention to provide a core barrel construction wherein the inner or stationary shell is resiliently maintained on its supporting surface on the bit by a force that is substantially constant at all times.

It is still another object of this invention to provide an arrangement wherein this pressure is so maintained automatically.

It is a still further object of this invention to provide a simplified and improved form of core catcher.

This invention possesses many other advantages, and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of this invention is best defined by the appended claims.

In the drawing:

Figure 1 is a vertical section, showing the core barrel assembled with a conventional core drill in operating position in a well bore;

Fig. 2 is a detail section on an enlarged scale of the upper end of the core barrel; and

Fig. 3 is a similar section of the lower end, showing the core catcher.

Referring to the drawing, a core drill generally indicated by 5 is shown which may be one of various types in common use. It includes a shell 6 secured at its upper end, by means of suitable coupling members 7 and 8, to the drill string, and carries at its lower end the core bit 10. Within the shell 6 is disposed the core barrel 12, which receives the core 13 as it is cut by bit 10, the core 13 remaining stationary while the drill rotates and advances downwardly.

To retain the core in the barrel when the drill is withdrawn from the bore, a core catcher 14 is provided at the lower end of the barrel. To prevent damage or destruction of the core by

contact with a rotating member, the barrel 12 is provided with an inner shell 16 for receiving the core and which is so supported relative to the drill that it may remain stationary while the latter is rotated. This protects the core.

The lower end of shell 16 rests on the core catcher 14 which in turn is supported in an annular recess 17 having a shoulder 18 in bit 10. The core catcher is free to turn on its support, and is restrained against upward movement by the shell 16.

The upper end of shell 16 is suitably supported for permitting relative rotation between shells 16 and 20, by a combined radial and thrust bearing 19 carried in the outer shell 20 of the core barrel. Bearing 19 is preferably of some anti-friction type so that the inner and outer shells are freely relatively rotatable under conditions of use. For example, a roller bearing may be used. It is not necessary to provide any bearing at the lower end of barrel 16, since when a core is being taken, the downward movement of the drill past the stationary core will create a force urging the core shell 16 upwardly against bearing 19 and tending to move the shell 16 off the core catcher 14 and shoulder 18. If no core is being taken, the inner shell 16 and the core catcher 14 rest on this shoulder, but in this case there is nothing to prevent the shell 16 from rotating with the bit. Hence the entire structure rotates together and no wear will occur on the shoulder and contacting parts.

Thus, the inner or stationary shell 16 is confined between shoulder 18 and bearing 19. As it is desirable that the shell be freely rotatable with respect to its supporting bearings, and at the same time that the clearance at shoulder 18 should be sufficiently close to substantially prevent passage of the circulation fluid from the inside of the barrel 12 into the core space at this point, means must be provided for holding the core shell 16 and core catcher 14 against shoulder 18. Manual adjustment of the axial position of the upper bearing 19, for providing a sufficient seat between the relatively moving parts, is difficult to make after the tool is assembled, and of course impossible while the tool is in the well. Further, since the length of the core barrel usually exceeds twenty feet, variations in temperature as well as other operating conditions would necessitate frequent adjustment. The requirement for adjustment is obviated in the present instance by a compression spring 21 confined within shell 20 and acting against bearing 19 to urge the inner shell 16 and the core catcher 14 downwardly to seat 18. The structure whereby the spring 21 is rendered effective will now be described.

The outer shell 20 is secured at its lower end to bit 10, as by a threaded portion 22, and

has its upper end closed by a cap 23, terminating in a conical portion 24, of which more will be said later. Slidable within cap 23 is a cup-like member 25, having a recess 26 in its bottom wherein the outer race 50 of bearing 19 is secured, as by a press fit. Spring 21 is confined between an annular shoulder 27 formed within the cup, and a wall 28 at the bottom of member 24, and urges member 25 downwardly. To prevent the spring 21 and cup 25 dropping out of cap 23 when this is removed from the barrel, the cup 25 has its midportion of reduced diameter, forming shoulders 29, 30. A stop pin 31 mounted in the wall of the cap 23 extends into this space, and by engaging shoulder 29 holds the cup from coming out of the cap but at the same time allows it to move in response to the movement of the inside shell. Spring 21 is strong enough to ensure that the frictional forces acting to move the inner shell 16 upwardly are overcome and to ensure a satisfactorily tight fit between the bottom of the shell 16 and the rotating bit structure.

The inner shell 16 is closed at its upper end by a head 32, threaded into shell 16. Head 32 is provided with ports 33 in its walls, some of which may be elongated to give greater area, to permit the discharge of circulation fluid or other well liquids from the inside of shell 16 as the core 13 rises therein. A hub 34 on top of the head 32 carries the inner race 51 of bearing 19, as by being pressed on. A plurality of conical rollers 35 secured in a cage 36 are interposed between the races in a well understood manner.

The lower end of the inner shell 16 rests on an annular shoulder 37 formed in ring 38 of core catcher 14. The lower part of the inside surface of this ring is bevelled at a fairly steep angle as indicated by 39. On this surface are secured as by rivets 40, a number of spring fingers 41. By this arrangement, the fingers 41 are given an upward and inward inclination without the necessity of bending them. The upper parts 42 of the fingers 41 are tapered to a point and are curved inwardly so as closely to approach each other. By having the fingers 41 straight at the point where the flexing occurs, a stronger and more resilient finger results; at the same time, the manufacture is simplified.

A protector ring 43 is used to cover the inside of the rivets and the lower parts of the springs, and is secured to ring 38 as by spot welding or brazing. The lower surface of this ring rests on shoulder 18. The method of assembly is obvious, no particular order of procedure being necessary.

The bit 10 as shown, has a plurality of blades 45 for cutting the well bore to the desired diameter. It also has an advanced portion 46 provided with teeth 47, this portion acting as a pilot or guide and also cutting the core 13.

Downwardly directed ports 48 having their discharge openings adjacent the lower edges of blades 45 serve to direct the circulation fluid. This fluid is forced downwardly through the drill string and reaches the ports through the annular space between shell 6 and the core barrel 12.

The conical cap 24 serves to direct this fluid, which may be heavy mud, into this annular space with a minimum of resistance. As core

13 rises within inner shell 16, the circulation fluid of mud therein is displaced outwardly through ports 33 into the annular space between shells 16 and 20, and thence downwardly and out into the well through ports 49.

As the core 13 passes into the inner shell 16 past the core catcher 14, the fingers 41 are bent outwardly as indicated in Fig. 1, the extent of this bending depending on the hardness of the core. Due to the closeness with which the upper ends 42 of the fingers 41 approach each other, the catcher will be effective to hold cores of very soft material.

The mud fluid entering the annular space between the inner and outer barrels 16 and 20, reaches the core catcher assembly and serves in some measure to lubricate the bearing between the inner core barrel 16 and the core catcher.

What is claimed is:

1. In a core drill, an outer rotary tubular member having a bit secured at its lower end, a core barrel including a rotary outer shell secured to the bit and an inner shell rotatably supported at its lower end on the bit and guided at its upper end by bearing means, a guide member slidable axially within the outer shell and supporting the bearing means, a closure for the upper end of the outer shell, and resilient means interposed between the guide member and the closure for urging the bearing and inner shell downwardly.

2. In a core drill, an outer rotary tubular member having a bit secured at its lower end, a core barrel within said shell, there being an annular space between the shell and the barrel to permit circulation fluid to pass downwardly to ports in the bit, said core barrel including a rotary outer shell secured to the bit and an inner shell rotatably supported at its lower end on the bit and guided at its upper end by bearing means, a guide member slidable axially within the outer shell and supporting the bearing means, a closure for the upper end of the outer shell, said closure being of tapered configuration so as to guide the circulation fluid into the annular space with low resistance, and resilient means interposed between the guide member and the closure for urging the bearing and inner shell downwardly.

3. In a core drill, an outer rotary tubular member having a bit secured at its lower end, a core barrel including a rotary outer shell secured to the bit and an inner shell rotatably supported at its lower end on the bit, said outer shell having an inner cylindrical guiding surface adjacent its upper end, and bearing means slidably supported by said guiding surface for maintaining the upper ends of said shells in axial alignment.

4. In a core drill, an outer rotary tubular member having a bit secured at its lower end, a core barrel including a rotary outer shell secured to the bit and an inner shell rotatably supported at its lower end on the bit, said outer shell having an inner cylindrical guiding surface adjacent its upper end, a combined radial and thrust bearing adjacent the upper end of the inner shell, said bearing being slidably supported for axial movement in said guiding surface, and means resiliently urging the bearing and the inner shell downwardly in the outer shell.

ALFRED MUHLBACH.
